CLAIM

The ornamental design for a self-supporting pouch attachment for medical articles, substantially as shown and described.

DESCRIPTION

FIG. 1 is a perspective view of a self-supporting pouch attachment for medical articles showing our new design;

FIG. 2 is a top plan view thereof;

FIG. 3 is a bottom plan view thereof;

FIG. 4 is a right side elevational view thereof; and the left side elevational view being a mirror image thereof; and,

FIG. 5 is a front elevational view thereof; the rear elevational view being a mirror image thereof.

The broken line drawing in all figure views is for illustrative purposes only, and forms no part of the claimed design.
